UNITED STATES PATENT OFFICE

2,418,327

ORNAMENTAL FABRIC FOR HANDBAGS

Daniel D. Whyte, Brooklyn, and Nicholas Klein, Laurelton, N. Y.; said Klein assignor to said Whyte

Application November 28, 1944, Serial No. 565,521

8 Claims. (Cl. 41—10)

1
This invention generally relates to flexible decorative materials, such as may be employed for coverings for handbags, pocketbooks, belts and other accessory articles of apparel, or similar products, and is specifically directed to a novel and improved material of this character as well as to the method of making the same.

Decorative coverings for handbags or the like have been heretofore generally produced by arranging a number of units side by side, in definite patterns or designs, and interconnecting or interlacing the units by means of tapes or the like traversing the units, usually at right angles to each other, through openings provided therein. The structure thus formed is then applied to the object to be covered by securing thereto the free ends of the tapes.

A material of the aforementioned character, while being substantially flexible and adapted for application to curved surfaces and in general flexible bodies, is not entirely satisfactory because of certain shortcomings inherent therein. In the first place, the manufacture of the material is comparatively complicated and expensive, due to the necessity of passing numerous tapes through a large number of openings, tensing the tapes accurately to insure proper interconnection of the units and securing all the ends of the tapes to the object to which the material is to be applied. A further serious defect of such structures consists in that the units are not interconnected at their base but in a plane above the base and only at points intermediate their sides. For this reason, and since the interconnecting means are flexible and cannot be tensed beyond a certain limit if sufficient flexibility is to be maintained, the adjacent units may become easily vertically displaced relative to each other and to the underlying surface of the article, so as to assume positions at different angles, whereby the walls of the article appear to break and open irregularly and sharply, in various directions, and the desired ornamental effect is seriously impaired.

The aforementioned defect, which is common to all materials of the character described employing interlaced units, is eliminated in other types of ornamental coverings in which the units are not interlaced but individually secured at their base to a backing sheet, by sewing. This method, however, besides being objectionable because of the considerable amount of sewing required and the presence of a number of exposed lines of stitching, necessarily involves the use of units formed with a flat base portion to be sewed to the backing sheet; therefore, the finished ma-

2
terial will always present decorative portions separated from each other by flat surfaces, with the resulting limitation in the range of ornamental effects attainable.

5 The primary object of the invention is therefore to provide a decorative material or covering of the character described, which, besides possessing a high degree of flexibility, is free of the defects inherent in the structures of the prior art, 10 consists of elements assembled in such a manner as to prevent any objectionable displacement thereof, and is simple and inexpensive to manufacture.

Another object of the invention is to provide 15 a method whereby the use of units interlaced by means of tapes or the like may be entirely dispensed with, and a decorative material having the desired requisites expeditiously produced without necessity of sewing the base of the units 20 upon a backing sheet. The method comprises the assembly of a plurality of preformed units and flexible elements adapted for interassociation in a predetermined manner, and the simultaneous connection of the units to the flexible elements 25 in a single operation.

A further and more specific object is to provide 30 a material consisting of rigid units associated with flexible elements in such a manner as to produce a longitudinally and transversely flexible structure, the rigid units being provided with portions whereby the units may be connected to the flexible elements at a plurality of spaced points adjacent their base.

35 It is also within the scope of the invention to provide units embodying portions deformable to permanently secure the units to associated flexible elements of the structure, in a final phase of the manufacture of the material.

These and other objects will become apparent 40 in the following description of the invention illustrated in the drawings, wherein:

Fig. 1 is a perspective view showing the inner 45 face of one of the units employed in the formation of a decorative material according to the invention.

Fig. 2 is a perspective view showing the outer 50 face of the unit of Fig. 1.

Fig. 3 is a perspective view of one of the flexible strips to be assembled with the units to form the complete material.

Fig. 4 is a bottom plan view of a portion of the decorative material in an intermediate phase of construction, illustrating the manner in which 55 the units and the flexible strips are assembled.

Fig. 5 is a vertical sectional view on line 5—5 of Fig. 4.

Fig. 6 is an enlarged vertical sectional view through a portion of the material, illustrating the final phase of formation thereof.

Fig. 7 is a bottom plan view of a portion of finished material.

Fig. 8 is a composite perspective view of portions of the material bent to illustrate the flexibility thereof.

Fig. 9 is a perspective view of a handbag embodying a covering of decorative material according to the invention.

Referring now in detail to the drawings, 10 designates the substantially rigid decorative units employed in the formation of the material, which, in the embodiment illustrated, are shown as shallow hollow formations or shells, of substantially square contour comprising a top wall 11 and a peripherally extending flange or wall 12. The outer face of the wall 11 may be provided with any desired design for the purpose of ornamentation.

The units 10 which may be made of a suitable moldable thermoplastic material, have, preferably formed integral therewith, projecting elements or pins 14 disposed at the corners of the hollow structure and extending, inwardly of the flange 12, from the inner face of the wall 11 to a point beyond the edge of the flange defining the base of the unit, for the purpose that will hereafter become apparent.

In the production of the material, the units, formed as described, are turned upside down to present upwardly extending pins 14, and are disposed side by side in a jig 15 (shown in Fig. 6), with their flanges 12 substantially in contacting relation, to provide series of longitudinal and transverse rows of aligned units, the pins 14 being therefore disposed in uniformly spaced aligned groups of four, each formed by pins of four contiguous units.

The rows of units are interconnected by means of a suitable material, preferably in the form of elements or strips 16, which, besides possessing a considerable degree of flexibility should also be strong and, preferably, capable of normally maintaining its shape. A cellulose acetate plastic may be, for instance, advantageously used in the formation of the strips, which are provided with groups of holes 17, uniformly spaced from each other for registration with the groups of pins 14.

A number of the strips 16 are laid upon the edges of the aligned flanges 12 of the units 10 of adjacent longitudinal rows and further strips are superimposed upon the strips so applied, at a right angle thereto, to overlie the edges of the aligned flanges 12 of the units of adjacent transverse rows, the pins 14 projecting through and beyond the holes 17 of the strips, aligned with the pins, as shown in Figs. 4 and 5. The structure is completed by means of peripheral strips 18, overlying the edges of the flanges 12 of the outermost units 10 and projecting outwardly of the periphery of the structure. Said peripheral strips 18 are identical to the strips 16, except in that their outwardly projecting portion is provided with a series of additional aligned holes 19, as shown in Fig. 4, for the purpose that will become later apparent.

The application of the strips, in the aforementioned relation to the rows of units, may be advantageously effected by feeding the flexible holed material from a plurality of rolls 21 (one of which is indicated in Fig. 5) suitably located laterally of

the jig 15, to place the groups of holes 17 in registration with the groups of pins 14, cutting the material to the required strip length and displacing the strips to their final position illustrated.

The units 10 and associated strips 15 and 18, assembled as described, are secured together to complete the formation of the material, in a final phase of the construction thereof and in a single operation. As illustrated in Fig. 6, for this purpose the portions of the pins extending beyond the strips 16 are subjected to the action of a pressure plate 20, under suitable pressure and heat determined in relation to the characteristics of the plastic material used for the units, and deformed to provide enlarged end portions or heads 22 forming abutments effective to prevent separation of the strips from the pins and to interlock the strips with the units in the relation described. A portion of finished material is shown in Fig. 7.

As will be apparent from the foregoing, the end product obtained comprises units that are secured to the strips 16 at their four corners, so that any objectionable relative displacement of the units and strips is positively prevented. On the other hand, the longitudinally and transversely extending rows of units are interconnected by the flexible strip material; relative angular movement of the rows of units is therefore permitted, and an articulated structure is formed which is longitudinally and transversely bendable in the manner illustrated in Fig. 8. In order to facilitate bending of the structure and prevent undue strain on the flexible strip material, the pins 14 loosely fit within the holes 17, these latter being of a somewhat greater diameter than the pins, so as to permit a limited displacement of the units relative to the associated strips, or, in other words, a limited expansion of the structure during bending.

The flexible decorative material produced as described is adapted for application to a variety of articles, as exemplified by the handbag 24 shown in Fig. 9, the material being readily applied and secured to the body of the article to be covered by means of lines of stitching passing through the aforementioned series of holes 19 provided in the peripheral strips 18.

The invention has been described substantially with reference to a preferred embodiment thereof; it is however to be understood that changes and modifications may be made in the structure illustrated, particularly with regard to the shape of the decorative units, the number, arrangement and connection to the units of the projecting elements or pins, and the character and conformation of the flexible material associated with the units, without departing from the spirit of the invention or exceeding the scope of the claims.

We claim:

1. A flexible decorative material comprising a number of substantially rigid units arranged to form longitudinally and transversely extending series of rows, a plurality of flexible strips juxtaposed to portions of the base of the units of adjacent longitudinal and transverse rows, and a plurality of elements projecting from each unit and passing through said flexible strips, said projecting elements having enlarged portions adapted to secure the flexible strips to the units.

2. A flexible decorative material comprising a number of substantially rigid decorative units arranged side by side to form longitudinally and transversely extending series of rows, a plurality of flexible strips juxtaposed to portions of the

5

units of adjacent longitudinal and transverse rows, each of said units embodying a plurality of integrally formed elements projecting therefrom and passing through the flexible strips, said projecting elements having enlarged end portions adapted to secure the flexible strips to the units.

3. A flexible decorative material comprising a number of decorative units arranged side by side substantially in peripheral contacting relation to form series of longitudinally and transversely extending series of rows, a plurality of flexible strips juxtaposed to portions of the units of adjacent longitudinal and transverse rows, each of said units embodying a plurality of spaced projecting elements arranged inwardly of the periphery thereof, said elements passing through the flexible strips and being formed at the ends thereof with retaining heads adapted to secure the flexible strips to the units, whereby to provide flexible interconnections for the adjacent rows of units. 15 20

4. A flexible decorative structure comprising a number of units of moldable plastic material arranged side by side to form series of longitudinally and transversely extending series of rows, a plurality of flexible strips juxtaposed to portions of the units of adjacent longitudinal and transverse rows, each of said units embodying a plurality of integrally formed spaced projecting elements passing through the flexible strips and having enlarged end portions providing abutments adapted to secure the flexible strips to the units.

5. A method of producing a decorative flexible material, which comprises forming a number of units embodying a plurality of elements projecting therefrom, arranging said units in side by side relation, interconnecting the projecting elements of adjacent units by means of a flexible material having holes for the passage of the projecting elements, and shaping the ends of the elements to form enlarged retaining portions adapted to prevent separation of the strips from the elements.

6. A method of producing a flexible decorative material, which comprises forming a number of substantially rigid decorative units embodying a

6

plurality of integral elements projecting therefrom, arranging said units side by side to provide a series of longitudinal and transverse rows of units, applying to the adjacent longitudinal and transverse rows of units a plurality of flexible strips provided with holes for the passage of said projecting elements of the units, and shaping the free ends of the projecting elements of the units to form retaining heads for the strips.

7. A method of producing a decorative flexible structure, which comprises forming a number of units of thermoplastic material embodying a plurality of integral spaced projecting elements, arranging said units in side by side relation, interconnecting the projecting elements of adjacent units by means of flexible strips having openings for the passage of the elements, and deforming the end portions of the elements under heat and pressure to permanently secure said flexible strips to the elements aforesaid.

8. A method of producing a decorative material, which comprises forming a number of units each embodying a plurality of elements projecting therefrom, arranging said units in side by side relation with their projecting elements extending upwardly, to form series of longitudinal and transverse rows of units, feeding a series of flexible strips having openings for alinement with projecting elements of the units of adjacent longitudinal and transverse rows, passing said projecting elements through said openings of the strips, and deforming the ends of the projecting elements to secure the strips to the units.
